F. D. HARLEY

NOVELTY DOLL

Filed July 17, 1924

INVENTOR.
FLORENCE DEMING HARLEY

BY Miller, Henry & Boyken
ATTORNEYS.

UNITED STATES PATENT OFFICE.

FLORENCE DEMING HARLEY, OF SAN FRANCISCO, CALIFORNIA.

DESIGN FOR A NOVELTY DOLL.

Application filed July 17, 1924. Serial No. 10,169. Term of patent 7 years.

To all whom it may concern:

Be it known that I, FLORENCE DEMING HARLEY, a citizen of the United States, and a resident of the city and county of San Francisco, State of California, have invented a new, original, and ornamental Design for a Novelty Doll, of which the following is a specification, reference being had to the accompanying drawing, forming a part thereof.

The figure is a front perspective view of a novelty doll showing my new design.

I claim:

The ornamental design for a novelty doll as shown.

Dated: San Francisco, Calif., this 10th day of July, 1924.

FLORENCE DEMING HARLEY.
